TUBULAR STRING CONTROL VALVE

Hiram H. Fisher, Jr., Houston, Tex., assignor to Baker Oil Tools, Inc., Los Angeles, Calif., a corporation of California

Application December 5, 1955, Serial No. 550,899

12 Claims. (Cl. 137—496)

The present invention relates to fluid valve devices, and more particularly to valve devices to be incorporated in tubular strings that are to be disposed in well bores.

In the running and use of tubular strings in well bores, such as tubing or drill pipe, it may be desirable to embody an upwardly closing back pressure valve therein to prevent upward flow of fluids into the tubular string. Such back pressure valve, however, will permit fluids or fluent materials to be pumped down through the tubular string to a location below the valve. The material pumped down through the tubular string may erosively wear the back pressure valve, particularly when such material embodies abrasive particles, like sand used in a hydraulic formation fracturing operation in the well bore, or abrasive laden drilling mud used in the drilling of the well bore.

An object of the present invention is to provide a back pressure valve device to be incorporated in a tubular string disposed in a well bore, which is capable of preventing upward flow of fluid in the tubular string during its lowering in the well bore, as well as at other times, the valve device being protected to prevent or minimize erosive wear therein when fluids are pumped down the tubular string.

Another object of the invention is to provide a back pressure valve device to be incorporated in a tubular string disposed in a well bore, which is capable of preventing upward flow of fluid in the tubular string, and in which downward flow of fluid therein automatically results in the protection of the valve device to prevent erosive wear thereon.

A further object of the invention is to provide a back pressure valve device of the character indicated, which is protected against erosive wear during the existence of a pressure differential within the tubular string above the valve.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section through a valve device, with the valve in closed position;

Fig. 2 is a view similar to Fig. 1, with the valve in open position;

Fig. 3 is a cross-section taken along the line 3—3 on Fig. 1;

Fig. 4 is a cross-section taken along the line 4—4 on Fig. 2.

The valve apparatus A disclosed in the drawings is 70

2

adapted to be incorporated in a tubular string B extending to the top of a well bore, by means of which the apparatus is run therein. The tubular string B may consist of tubing or drill pipe, or the like, extending to the top of the hole, the valve device itself ordinarily being secured to another subsurface tool C therebelow.

As specifically shown, the valve device A includes an outer tubular housing 10 formed in several sections. Thus, an upper housing section 11 has an upper threaded box 12 threadedly mounted onto the lower pin end 13 of a section of tubing or drill pipe B. The lower portion of the upper housing 11 is threadedly secured within the upper threaded box portion 14 of a lower housing section 15, which has a threaded box 16 threadedly attached to the upper pin end 17 of the lower tool C, which may be the body portion of a lower packer. If the apparatus is incorporated in a string of drill pipe used for rotating a drill bit, the lower tool C may be a drill collar or a drill bit.

The upper housing section 11 has an upper head portion 18 extending inwardly from an enlarged cylinder housing bore 19 which extends downwardly from the upper head portion to an intermediate head 20 threadedly secured to the upper portion of the lower housing section 15 adjacent the lower end 21 of the upper housing section. This intermediate head 20 has a bore 22 therethrough, which is surrounded by a downwardly facing valve seat 23 adapted to be engaged by a valve head 24 that can be disposed within an enlarged chamber portion 25 between the lower end of the intermediate head 20 and the upper end of a lower head 26 extending inwardly from the main portion of the lower housing section 15.

The valve head 24 is movable upwardly into engagement with the downwardly facing valve seat 23 to prevent upward flow of fluid through the valve apparatus. It is in the form of a flapper valve head suitably fixed to an arm 27 having outer bifurcations 28 pivotally mounted upon a hinge or pivot pin 29 extending transversely through a pair of spaced lugs 30, which depend from the intermediate head 20 adjacent the inner wall 31 of the enlarged chamber. The flapper valve head 24 tends to drop by gravity into a generally vertical position completely displaced from the path of downward fluid travel 45 through the valve apparatus. The valve head 24 is swingable upwardly into engagement with the valve seat 23, being urged toward such position by a spring 32, including an intermediate coil portion 33 wound around the hinge pin 29 between the lugs 30. From the coil portion 33, a spring arm 34 extends across the valve head arm 27, tending to urge it upwardly, unwinding of the coil portion of the spring being prevented by another spring arm 35 extending from the coil portion and engaging the intermediate housing head 20.

The spring 32 urges the valve head 24 upwardly into engagement with the valve seat 23, but the valve head can, nevertheless, be moved downwardly against the force of the spring to an open position. To insure against leakage of fluid between the valve head 24 and the seat 23, the latter may have an annular groove 36 therein, receiving a suitable seal ring 37, such as a rubber O-ring, which will engage the marginal portions of the sealing face 38 of the valve head. Proper sealing engagement of the sealing face 38 against the valve seat 23 and the seal ring 37 can be achieved by having the openings in the arms 28 through which the hinge pin 29 passes elongated in a direction normal to the plane of the head 24, so that the head can shift appropriately in a longitudinal direction when engaged with its seat 23.

When the apparatus so far described is secured to the

tubular string B and is lowered in the well bore, any fluid in the latter will hold the valve head 24 upwardly against its seat 23, preventing entry of such fluid in an upward direction into the string B. Similarly, assuming that the apparatus is used in connection with a well packer, or the like, any tendency for fluid to flow upwardly into the tubular string B will be precluded by the upward movement of the valve head 23 and its sealing engagement against the valve seat 23. It is apparent that the valve functions as a back pressure valve, tending to prevent upward flow of fluid in the tubular string B. However, the head 24 can swing downwardly away from its seat 23, so as not to prevent downward flow of fluid in the tubular string.

During the downward passage of fluid in the tubular string B, such fluids could impinge upon the valve head 24, and even upon the valve seat 23, in view of the turbulence that would be created as the fluid discharged into the valve chamber 25, causing erosive wear on the parts and, at times, shortening the life of the valve device to a considerable extent. Such erosive wear would be most pronounced when sand laden fluids were pumped down the tubular string B during the performance of a hydraulic formation fracturing operation in the well bore, which is usually conducted in conjunction with a packer C anchored in packed-off condition in a well casing (not shown). Accordingly, after the operation in the well bore has been performed, the upward movement of the valve head 24 into engagement with its seat 23, to close the valve, might result in leakage thereby, if not complete failure of the valve mechanism. Similarly, if the back pressure valve were employed as a drill pipe float valve device, then the downward pumping of drilling mud, and the like, through the string of drill pipe B and through the valve device A would result in erosive wear on the valve parts, wherein they would be unavailable for sealing the drill pipe B against upward flow of fluid therein, in the event a blowout tended to occur during the drilling operation.

The present invention prevents the erosive wear on the back pressure valve device by protecting the latter. Such protection can be complete, as by fully covering the flapper valve head 24 and preventing any fluent materials pumped down the tubular string B and through the valve device A from engaging the flapper valve head 24. For that matter, such fluids are even prevented from having any effect upon the valve seat 23 and its seal ring 37.

As specifically disclosed, a valve controlling tubular sleeve member 40 is slidably mounted in the housing 10. This sleeve member includes a lower portion 41 slidable in the intermediate head 20, this lower portion preferably terminating in a downward and inwardly tapering end 42. The lower sleeve portion 41 is integral with an intermediate portion 43 of larger outside diameter than the lower portion, which, in turn, is integral with an upper portion 44 that may be considered as a piston of still greater diameter than the intermediate portion, this piston being slidably along the enlarged cylinder bore 19 of the housing 10.

The tubular control sleeve 40 preferably has a cylindrical inner bore 45 of a diameter at least equal to the diameter of the bore of the tubular string, to which the valve apparatus is connected, so that no restrictions to downward flow of fluid through the apparatus are provided by the sleeve 40 itself. To insure the proper guiding of fluent substances downwardly into and through the sleeve 40, the upper portion 46 of its bore may be inclined in an upward and outward direction.

The control sleeve 40 is adapted to occupy an upper position within the housing 10, determined by engagement of its upper end with the upper head 18, in which position the lower end 42 of the sleeve is disposed above the valve seat 23. When in this position, the control

sleeve 40 will not preclude upward swinging of the flapper valve head 24 into appropriate sealing engagement with the valve seat 23 and its seal ring 37. The sleeve 40, however, can be shifted downwardly in the housing 10 to the extent determined by engagement of the stop shoulder 47, provided by the lower end of the intermediate diameter portion 43, with a companion stop shoulder 48 projecting upwardly from the intermediate head 20, in which position the lower portion 41 of the sleeve valve is disposed within the central bore 49 through the lower housing head 26 and completely across the flapper valve head 24. When the sleeve valve is in this position, fluid pumped downwardly through the tubular string B will continue on through the control sleeve 40 and down through the lower head 26 and into the lower tool or tubular member C connected to the lower head. Inasmuch as the protective sleeve 40 completely covers the flapper valve head 24, no fluids or fluent substances can impinge upon the latter, since it is fully protected. Fluids are prevented from entering the chamber 25 containing the valve head 24 and the valve seat 23, which precludes any fluid turbulence within the chamber that might have any deleterious effect upon the valve seat 23 and its seal ring 37.

25 The control sleeve 40 is normally urged toward its upper position, free from interference with the flapper valve head 24, by a helical compression spring 50 disposed around the control sleeve within the housing between the intermediate head 20 and the piston 44. This spring exerts adequate force tending to elevate the control sleeve 40 to its maximum upward position in engagement with the upper housing head 18. When in this position, as described above, the lower end 42 of the control sleeve is disposed substantially above the location of the valve seat 23, and will not interfere with upward movement of the valve head 24 into engagement with the latter and its seal ring 37. When a fluid pressure differential is present within the tubular string, such as accompanies the pumping of fluent material downwardly through the latter, then such fluid pressure is effective to shift the sleeve 40 to its downward position against the force of the spring 50, to completely cover the valve head 24 and shift the lower portion 41 of the control sleeve into the lower head bore 49. Such action occurs hydraulically and automatically.

Leakage of fluid in both directions between the piston 44 at the upper end of the control sleeve and the wall 19 of the cylinder is prevented by appropriate seal rings 51, which are received within peripheral grooves 52 in the piston and which slidably seal against the cylinder wall. Leakage of fluid between the lower portion 41 of the control sleeve and the intermediate housing head 20 is prevented by one or more seal rings 53, such as rubber or rubber like O rings, disposed in an internal circumferential groove 54 in the intermediate head, and slidably sealing against the periphery of the lower portion 41 of the control sleeve.

It is apparent that the annular area R of the upper piston portion 44 of the control sleeve 40, over which fluid pressure within the apparatus is acting, is substantially greater than the annular area S across the lower end of the small diameter portion 41 of the control sleeve. Accordingly, there is a differential area facing in an upward direction and over which the fluid pressure within the tubular string B and apparatus A is acting, to provide a substantial force capable of shifting the control sleeve 40 downwardly against the resisting force of the return spring 50. Whenever a pressure differential exists within the tubular string B in an amount capable of overcoming the resisting force of the helical spring 50, the control sleeve 40 is shifted downwardly to displace the valve head 24 completely to one side, fully covering such valve head and bridging the chamber 25 in which it is confined. Downward movement of the control sleeve 40 within the housing 10 is facilitated by bleeder holes

55 provided at the lower portion of the upper housing section 11, which will allow fluid to flow freely between the region externally of the housing 10 and the annular space 56 between the control sleeve 40 and the housing.

The specific apparatus A described has several uses. If secured to the upper portion of a lower packer C and run in the well bore on a tubular string B, the control sleeve 40 will occupy its upper position during the lowering of the apparatus in the well bore, with the valve head 24 engaging the valve seat 23, to prevent upward flow of fluid through the valve apparatus and into the tubular string thereabove. When fluent materials are pumped down the tubular string, the pressure differential will act in a downward direction over the control sleeve 40, shifting it downwardly against the force of the spring 50, to displace the valve head 24 completely to one side of the central passage through the apparatus, with the lower portion 41 of the control sleeve extending into the lower head bore 49. The fluent material can then pass completely through the apparatus without acting upon the valve head 24 or its seat 23. Upon the relieving of the pressure within the tubular string B, the spring 50 will elevate the sleeve 40 above the valve seat 23, whereupon the spring 32 will engage the valve head 24 with its seat. Any tendency for fluid to pass upwardly through the valve head is thereby prevented, which will preclude the return flow of any fluent material that may have been pumped down through the tubular string B, back thereto. The tubular string B and apparatus A may be elevated in the well bore, and if there is any tendency for fluent materials, either gaseous liquid, or combination thereof containing relatively solid material, to flow upwardly, the valve head 24 will engage its companion seat 23 and prevent such upward flow of fluent materials.

Accordingly, it is evident that a back pressure valve has been provided which is available to prevent upward flow of fluid in the tubular string whenever such tendency occurs. Yet fluids can be pumped down the tubular string B and through the apparatus A without contacting the back pressure valve parts and erosively wear and damage the same.

The apparatus A can also be used as a drill pipe float valve to enable a string of drill pipe B to be floated in the well bore, and also to prevent blowouts in the well bore. During the lowering of the string of drill pipe B in the well bore, the flapper valve head 24 will engage its seat 23 preventing fluid from entering the drill pipe. When the drilling operation is to commence, the mere pumping of drilling fluid down through the string of drill pipe B will shift the control sleeve 40 to its lower position, displacing the valve head completely to one side of the apparatus and placing the lower portion 41 of the control sleeve within the lower head bore 49, in which position it completely protects the valve head, as well as the valve seat 23. Accordingly, any tendency for drilling mud, or other drilling fluids, to erosively wear the parts is completely eliminated. So long as fluid is being pumped down through the drilling string, the control valve head 24 is displaced to one side. However, should a blowout tend to occur, then the greater pressures from below will immediately shift the control sleeve 40 back to its upper position, and will allow the valve head 24 to swing upwardly into engagement with the valve seat 23. The predominant pressure below the latter will act over the whole area of the control sleeve 40 to return it to its upper position free from an engaging relation with the flapper valve head 24, since fluid under pressure can act in an upward direction over the annular area S of the lower control valve portion 41, and also pass through the bleeder holes 55 for upward action on the downwardly facing stop shoulder 47 and downwardly facing portion of the piston 44.

Accordingly, it is evident that the apparatus can be used as a drill pipe float and function as a safety device in pre-

venting blowouts, as well as enabling the drill string B to be floated into the well bore. However, during the actual drilling operation in the well bore, the back pressure valve 24 is completely protected from the erosive action of the drilling mud.

The inventor claims:

1. In valve apparatus: a housing adapted to be secured in a tubular string disposable in a well bore and through which fluid from the tubular string can flow, said housing being movable in the well bore with the tubular string; back pressure valve means in said housing adapted to open to permit flow of fluid from the tubular string through said housing in one longitudinal direction and adapted to close to prevent flow of fluid through said housing and into the tubular string in the opposite longitudinal direction; and means through which fluid from the tubular string can flow and shiftable by fluid pressure in the tubular string and said housing into engagement with said back pressure valve means to hold said back pressure valve means in open condition while permitting flow of fluid from the tubular string through said housing in said one longitudinal direction, said shiftable means having means associated therewith whereby said shiftable means is movable from engagement with said back pressure valve means when fluid tends to flow in said housing in the opposite longitudinal direction to allow said back pressure means to close.
2. In valve apparatus: a housing adapted to be secured in a tubular string disposable in a well bore and through which fluid from the tubular string can flow, said housing being movable in the well bore with the tubular string; back pressure valve means in said housing adapted to open to permit flow of fluid from the tubular string through said housing in one longitudinal direction and adapted to close to prevent flow of fluid through said housing and into the tubular string in the opposite longitudinal direction; means through which fluid from the tubular string can flow and shiftable by fluid pressure in the tubular string and said housing into engagement with said back pressure valve means to hold said back pressure valve means engaging said shifting means in open condition while permitting flow of fluid from the tubular string through said housing in said one longitudinal direction; and means for shifting said shiftable means out of engagement with the back pressure valve means to allow said back pressure valve means to close.
3. In valve apparatus: a housing adapted to be secured in a tubular string disposable in a well bore and through which fluid from the tubular string can flow, said housing being movable in the well bore with the tubular string, said housing having a valve seat; a valve head movable into engagement with said seat to prevent flow of fluid in said housing in one longitudinal direction; means for disposing said valve head out of engagement with said seat to one side of said housing to permit flow of fluid from the tubular string in said housing in the opposite longitudinal direction; and a control member in said housing shiftable by fluid pressure in the tubular string and said housing into engagement with and substantially fully across said head to hold said head out of engagement with said seat to one side of said housing to prevent substantial contact of said head by fluid flowing from the tubular string through said housing in said opposite longitudinal direction, said control member having means associated therewith whereby said control member is movable from engagement with said head when fluid tends to flow in said housing in said one longitudinal direction to allow said head to engage said seat.
4. In valve apparatus: a housing adapted to be secured in a tubular string disposable in a well bore and through which fluid from the tubular string can flow, said housing being movable in the well bore with the tubular string, said housing having a valve seat; a valve head movable into engagement with said seat to prevent flow of fluid in said housing in one longitudinal direction; means

for disposing said valve head out of engagement with said seat to one side of said housing to permit flow of fluid from the tubular string in said housing in the opposite longitudinal direction; a control member in said housing shiftable by fluid pressure in the tubular string and said housing into engagement with and substantially fully across said head to hold said head out of engagement with said seat to one side of said housing to prevent substantial contact of said head by fluid flowing from the tubular string through said housing in said opposite longitudinal direction; and means for shifting said control member out of engagement with said head to allow said head to engage said seat.

5. In valve apparatus: a housing adapted to be secured in a tubular string disposable in a well bore and through which fluid from the tubular string can flow, said housing being movable in the well bore with the tubular string, said housing having a valve seat; a valve head movable upwardly into engagement with said seat to prevent upward flow of fluid in said housing; means for disposing said valve head downwardly and out of engagement with said seat to one side of said housing to permit downward flow of fluid from the tubular string in said housing; and a control sleeve in said housing shiftable by fluid pressure in the tubular string and said housing downwardly into engagement with and completely across said head to hold said head out of engagement with said seat completely to one side of said housing to enable fluid to flow downwardly from the tubular string through said housing and sleeve without contacting said head, said control sleeve having means associated therewith, whereby said control sleeve is movable upwardly from engagement with said head when fluid tends to flow upwardly in said housing to allow said head to engage said seat.

6. In valve apparatus: a housing adapted to be secured in a tubular string disposable in a well bore and through which fluid from the tubular string can flow, said housing being movable in the well bore with the tubular string, said housing having a valve seat; a valve head movable upwardly into engagement with said seat to prevent upward flow of fluid in said housing; means for disposing said valve head downwardly and out of engagement with said seat to one side of said housing to permit downward flow of fluid from the tubular string in said housing; a control sleeve in said housing shiftable by fluid pressure in the tubular string and said housing downwardly into engagement with and completely across said head to hold said head out of engagement with said seat completely to one side of said housing to enable fluid to flow downwardly from the tubular string through said housing and sleeve without contacting said head; and spring means engaging said sleeve to shift said sleeve upwardly in said housing out of engagement with said head to allow said head to engage said seat.

7. In valve apparatus: a housing adapted to be secured in a tubular string disposable in a well bore and through which fluid from the tubular string can flow, said housing being movable in the well bore with the tubular string, said housing having a valve seat; a valve head movable upwardly into engagement with said seat to prevent upward flow of fluid in said housing; means for disposing said valve head downwardly and out of engagement with said seat to one side of said housing to permit downward flow of fluid from the tubular string in said housing; and a control sleeve in said housing having a resultant upwardly facing pressure actuatable area subject to the pressure of fluid in the tubular string and said housing above said sleeve to shift said sleeve downwardly into engagement with and completely across said head to hold said head out of engagement with said seat completely to one side of said housing to shield said head from fluid flowing downwardly through said housing and sleeve, said control sleeve having means associated therewith, whereby said control sleeve is movable upwardly from engagement with said

ment with said head when fluid tends to flow upwardly in said housing to allow said head to engage said seat.

8. In valve apparatus: a housing adapted to be secured in a tubular string disposable in a well bore, said housing having a central passage surrounded by a valve seat and through which fluid from the tubular string can flow; a valve head pivotally mounted on said housing and swingable upwardly into engagement with said seat; and a control sleeve in said passage shiftable by fluid pressure in the tubular string and said housing downwardly into engagement with and across said head to hold said head out of engagement with said seat, said control sleeve having means associated therewith whereby said control sleeve is movable upwardly from engagement with said head when fluid tends to flow upwardly in said housing to allow said head to engage said seat.

9. In valve apparatus: a housing adapted to be secured in a tubular string disposable in a well bore, said housing having a central passage surrounded by a valve seat and through which fluid from the tubular string can flow; a valve head pivotally mounted on said housing and swingable upwardly into engagement with said seat; a control sleeve in said passage shiftable by fluid in the tubular string and said housing downwardly into engagement with and across said head to hold said head out of engagement with said seat; and spring means in said housing engaging said sleeve to shift said sleeve upwardly out of engagement with said head to allow said head to engage said seat.

10. In valve apparatus: a housing adapted to be secured in a tubular string disposable in a well bore, said housing having an upper central passage surrounded by a valve seat and a lower central passage, both of said passages being communicable with the tubular string to receive fluid therefrom; a valve head between said passages pivotally mounted on said housing and swingable upwardly into engagement with said seat; and a control sleeve in said upper passage shiftable by fluid pressure in the tubular string and said housing downwardly completely across said head and into said lower passage to hold said head from said seat completely to one side of said passages to prevent contact of said head by fluid flowing downwardly from the tubular string through said housing and sleeve, said control sleeve having means associated therewith whereby said control sleeve is movable upwardly from engagement with said head when fluid tends to flow upwardly in said housing to allow said head to engage said seat.

11. In valve apparatus: a housing adapted to be secured in a tubular string disposable in a well bore, said housing having an upper central passage surrounded by a valve seat and a lower central passage, both of said passages being communicable with the tubular string to receive fluid therefrom; a valve head between said passages pivotally mounted on said housing and swingable upwardly into engagement with said seat; and a control sleeve in said upper passage having a resultant upwardly facing pressure actuatable area subject to the pressure of fluid in the tubular string and said housing above said sleeve to shift said

55 sleeve downwardly completely across said head and into said lower passage to hold said head from said seat completely to one side of said passage to prevent contact of said head by fluid flowing downwardly from the tubular string through said housing and sleeve, said control sleeve having means associated therewith whereby said control sleeve is movable upwardly from engagement with said head when fluid tends to flow upwardly in said housing to allow said head to engage said seat.

12. In valve apparatus: a housing adapted to be secured in a tubular string disposable in a well bore, said housing having an upper central passage surrounded by a valve seat and a lower central passage, both of said passages being communicable with the tubular string to receive fluid therefrom; a valve head between said passages pivotally mounted on said housing and swingable upwardly into engagement with said seat; and a control sleeve in said upper passage having a resultant upwardly facing pressure actuatable area subject to the pressure of fluid in the tubular string and said housing above said sleeve to shift said sleeve downwardly completely across said head and into said lower passage to hold said head from said seat completely to one side of said passage to prevent contact of said head by fluid flowing downwardly from the tubular string through said housing and sleeve, said control sleeve having means associated therewith whereby said control sleeve is movable upwardly from engagement with said head when fluid tends to flow upwardly in said housing to allow said head to engage said seat.

into engagement with said seat; a control sleeve in said upper passage having a resultant upwardly facing pressure actuatable area subject to the pressure of fluid in the tubular string and said housing above said sleeve to shift said sleeve downwardly completely across said head and into said lower passage to hold said head from said seat completely to one side of said passage to prevent contact of said head by fluid flowing downwardly from the tubular string through said housing and sleeve; and spring means engaging said sleeve to shift said sleeve upwardly 10 to permit said head to engage said seat.
